UNITED STATES PATENT OFFICE.

EVERETT M. BOCK, OF ELKHART, ILLINOIS.

RAILWAY-CROSSING SIGNAL.

Application filed August 25, 1922. Serial No. 584,234.

To all whom it may concern:

Be it known that I, EVERETT M. BOCK, a citizen of the United States, residing at Elkhart, in the county of Logan and State 5 of Illinois, have invented a new and useful Railway-Crossing Signal, of which the following is a specification.

The invention relates to signaling apparatus installed at places where railway 10 tracks cross roads or streets, to give timely warning to persons traveling on the road or street, of the approach of a train running on the track in either direction.

The purposes of the invention are to provide 15 a semaphore of improved construction; to provide improved means whereby the train approaching the crossing will operate the semaphore to give due warning to persons approaching the crossing; to provide 20 improved means whereby the train going away from the crossing in either direction will operate the semaphore to indicate that the track may be safely crossed by persons traveling on the road or street; and to provide 25 a simple and effective apparatus which may be installed at relatively small cost.

With these ends in view the invention consists in the novel features of construction and combinations of parts shown in the accompanying 30 drawings and now to be described and finally recited in the claims.

Referring to the drawings, in which the same reference numerals designate the same parts in all the views, Fig. 1 is a diagrammatic top plan of an installation embodying 35 my invention.

Fig. 2 is a diagrammatic side elevation of the same installation; Fig. 3 is a vertical section taken on the line 3—3 of Fig. 2, looking 40 towards the right; Fig. 4 is a vertical section taken on the line 4—4 of Fig. 2 looking towards the left; Fig. 5 is an enlarged top plan of the semaphore and apertures; Fig. 6 is a vertical section through 45 the semaphore taken on the line 6—6 of Fig. 5 looking towards the left; Fig. 7 is an enlarged top plan of one operating lever; Fig. 8 is a vertical section through one operating lever, taken on the line 8—8 of Fig. 7. Fig. 9 is an enlarged perspective 50 view of the actuator; and Fig. 10 is a vertical section through the actuator taken on the line 10—10 of Fig. 9.

The semaphore comprises a vertical standard 55 12 firmly secured in a concrete base 13; a hollow staff 14 rotative on the upper end

of the standard and a semaphore arm 15 attached at the upper end of the staff. In the lower part of the staff is a longitudinal bore 16 accommodating a coiled spring 17 surrounding the standard and having one end attached to the standard and the other end attached to the staff in such manner that clock-wise rotation of the staff will stress the spring and the spring will act to effect reverse rotation of the staff. A circular plate 18 fixed on the staff, has a radially extended stop 19. A latch 20 pivoted on a stationary support 21, is pressed against the perimeter of the plate 18 by a spring 22. The latch yields to permit counter clock-wise rotation of the staff and engages the stop 19 to limit clock-wise rotation of the staff.

A rectangular frame comprising four arms 23, 24, 25 and 26, associated as shown in Fig. 5 is firmly attached to and rotates with the staff 14.

As a matter of convenience, I have shown and will describe the signaling apparatus in operative relation to a straight railway track 80 A extending from east to west and crossed by a highway B at right angles to the track, but it is obvious that the track may be curved or may extend in different directions and that the highway may cross at different angles without impairing the effectiveness of the signaling apparatus.

The characters E¹ and E² designate the respective levers operative by trains going eastward, and the exponents indicate the order in which the levers are operated. The lever E¹ effects retraction of the latch 20 and the lever E² effects clock-wise rotation of the staff 14 to stress the spring 17.

The characters W¹ and W² designate the respective levers operative by trains going westward and the exponents indicate the order in which the levers are operated. The lever W¹ effects retraction of the latch and the lever W² effects clock-wise rotation of the staff.

In the diagrams (Figs. 1 and 2) I have indicated a compact assembly of the elements of the apparatus, but it is to be understood that in practice the installation will extend a "block" of sufficient length to accommodate a long train on the track on each side of the highway; that the latch operating levers E¹ and W¹ are at the respective ends of the block and will be operated by trains entering the block, and the levers E² and W² are adjacent to the highway.

The lever E^2 will be operated by eastward going trains immediately after the head of the train has crossed the highway; and the lever W^2 will be operated by westward going trains immediately after the head of the train has crossed the highway.

Upon retraction of the latch 20 the spring 17 will act to effect a quarter revolution of the staff 14 to cause the semaphore arm 15 to 10 occupy a position transverse to the highway B and remain in that position until the head of the train shall have crossed the highway.

The levers E^1 and W^1 are oscillative in 15 suitable bearings 30 and 31 on stationary blocks 32 and 33. Springs 34 contacting with the levers yield to permit depressing of the respective levers and act to return the depressed lever to its vertical position after 20 each depressing of the lever.

The lever E^1 is directly connected with the latch 20 by a suitable connecting device, preferably a wire 35 which pulls on the latch to withdraw its point from the 25 stop 19 when the upper end of the lever is pushed in the direction indicated by the arrow 36. (Fig. 2.)

The block 33 extends under the track. The lever W^1 has a downwardly extended 30 member 37 directly connected with the latch 20 by a wire 38 or other suitable connecting device, which pulls on the latch 20 to withdraw its point from the stop 19 whenever the upper end of the lever W^1 is pushed in the 35 direction indicated by the arrow 39.

The lever E^2 is oscillative in bearings 44 on a stationary block 45 and is connected with the arm 24, by a connecting device preferably consisting of a wire or cable 46 and a 40 terminal chain 48, giving flexibility to the connection. The connecting device pulls on the arm 24 to effect a quarter rotation clockwise of the staff 14 to stress the spring 16 to cause the semaphore arm 15 to occupy its 45 original position at right angles to the track in readiness for the next counter-clockwise rotation of the staff.

The lever W^2 is oscillated in bearings 40 on a sill 41 which extends under the track 50 and has an upwardly extended member 42 which is connected with the arm 26 by a flexible connecting device comprising a wire or cable 43 and a terminal chain 47 which 55 pulls on the arm to effect a quarter revolution clock-wise of the staff 14 to stress the spring 17 and permit the latch 20 to engage the stop 19 to hold the staff in such position that the semaphore arm 15 will be at right angles to the track, in readiness for the 60 next counter-clockwise rotation of the staff.

The work of the levers E^1 and W^1 is comparatively light inasmuch as they operate only the latch 20; but the work of the levers E^2 and W^2 is much greater because 65 they have to act in opposition to the main

spring 17. I therefore equip the levers E^2 and W^2 with shock absorbers which will now be described.

The levers E^2 and W^2 are preferably made of gas pipe and the upright members of 70 said levers are equipped with shock absorbers to absorb part of the shock due to the impact of the rapidly moving actuator.

Each shock absorber comprises a coiled spring 50 secured in and extending upwardly 75 beyond the upper end of the lever¹ a rubber cushion 51 surrounding the spring and wire 57 wound around the cushion and securing it on the lever.

A spring 49 is coiled around the horizontal 80 member of the lever. The lower terminal 49^a of the spring bears on the sill 41 and its upper part acts on the upwardly extended member of the lever to normally keep the lever in vertical position, but yields to permit the lever to be depressed by the actuator.

The parts 50 and 51 yield somewhat under the first shock delivered by the actuator, but are nevertheless sufficiently rigid to effect 90 downward turning of the upper end of the lever, resulting in one quarter clockwise rotation of the semaphore staff to place the semaphore arm in a position transverse to the highway.

The actuator C comprises a supporting 95 bar 52 provided with holes 53 to receive bolts for securing the bar on the tender of a locomotive in such position that the bar will extend outwardly above the upper ends of the operating levers E^1 , E^2 , W^1 and W^2 ; a block 100 53 supported by and extended downwardly below the bar, a hinge 55 connecting the block with the bar and a roller 56 rotative in bearings in the block. When the tender goes forwardly the roller will ride on and depress the levers E^1 and E^2 when going eastward, and will ride on and depress the levers W^1 and W^2 when going westward.

When the tender is going rearwardly, the roller 56 will engage the upper ends 110 of the operating levers and will cause the block 54 to swing outwardly on the hinge 55 to permit the roller to pass the levers without operating them.

I believe that I am the first to devise and 115 use a stationary vertical standard and a spring-actuated staff rotative on the standard and carrying a semaphore arm, and to devise and use the simple system of levers co-acting with the staff and the spring which 120 actuates it. A practical advantage of the construction herein set forth is that the semaphore has only one bearing, friction is avoided and the strain and wear of the operating parts is reduced to minimum.

The operation of the apparatus is obvious 125 from the foregoing description.

I am aware that actuators connected with moving trains have been used. I therefore do not claim that feature broadly.

What I claim as new and desire to secure by Letters Patent is—

In a signaling device, the combination of a stationary vertical standard, a tubular semaphore staff rotative on the upper end of the standard; a coiled spring surrounding said standard and having one end attached to the standard and the other end attached to the staff; a frame secured on the staff and having outwardly extended arms; levers and connections pulling on the arms of said frame to rotate the staff to stress said coiled spring; a latch plate attached to the staff and pro-

vided with a stop; a latch pivoted on a stationary support and adapted to engage the stop on said latch plate, and levers and connections effective to retract said latch to permit said coiled spring to rotate said staff.

In witness whereof I have hereunto signed my name at Elkhart, Illinois, this 16th day 20 of August, 1922.

EVERETT M. BOCK.
